UNITED STATES PATENT OFFICE.

NORMAN W. CUMMINS, OF BRIDGEPORT, CONNECTICUT, ASSIGNOR TO THE BURNS & BASSICK COMPANY, OF BRIDGEPORT, CONNECTICUT, A CORPORATION OF CONNECTICUT.

LUBRICATOR.

1,069,925.

Specification of Letters Patent. Patented Aug. 12, 1913.

Application filed September 6, 1912. Serial No. 718,877.

To all whom it may concern:

Be it known that I, NORMAN W. CUMMINS, a citizen of the United States, residing in the city of Bridgeport, county of 5 Fairfield, and State of Connecticut, have invented certain new and useful Improvements in Lubricators; and I do declare the following to be a full, clear, and exact description of the invention, such as will enable others skilled in the art to which it 10 appertains to make and use the same.

My invention relates to certain improvements in lubricators, but more particularly has reference to that type of lubricators 15 known as "grease cups" in which grease is contained within a suitable casing and is forced therefrom to the bearing to be lubricated by means of a plunger device.

The object of my improvement is to provide 20 a device of this description that shall be exceedingly simple in construction and effective in operation, and with these ends in view my invention consists in the details of construction and combination of parts 25 hereinafter fully described and then particularly pointed out in the claims which conclude this description.

A preferred embodiment of the improved 30 lubricator has been shown in vertical section in the accompanying drawing.

Similar numerals of reference denote like parts in both figures of the drawings.

1 is a casing which is interiorly threaded as shown at 2 and terminates at the bottom 35 in a threaded nozzle 3 for attachment to any bearing to be lubricated through which nozzle the grease is forced to the bearing.

4 is a cap which rests upon the upper edge of the casing, and 5 is a cover outside the 40 cap and secured to the upper portion of the casing in any suitable manner in the present instance by a frictional engagement therewith, said cover serving to prevent displacement of the cap 4 while at the same 45 time the latter is free to rotate.

6 is a stem which depends within the casing and is provided at the upper end immediately beyond the cover 5 with a handle 7. This stem extends freely through the top 50 of the cover 5 so as to be capable of free rotation and is provided with a collar 8 which rests on top of the cover and also with a collar 9 which extends immediately beneath the cap 4 so that it will be clear that 55 said stem is incapable of lengthwise move-

ment. This stem is rectangular in shape in cross section and extends through a rectangular opening in the cap 4 so that the latter will partake of the rotary movements of the stem.

10 is a plunger cup externally threaded and engaging the internal threads of the casing 1, said cup being inverted, and the rectangular stem 6 extends freely through a rectangular opening in the central portion of this cup, so that said cup will partake of the rotary movements of the stem but at the same time will be capable of free lengthwise movements along the stem. Contained within this cup is a packing 11 70 which snugly embraces the stem 6 so as to act as a gasket to prevent the grease from working upward along the stem, and the bottom of the latter is slightly enlarged as seen at 12 to prevent the cup 10 from leaving the stem. The casing immediately below the cup 10 is filled with grease, and as the stem is revolved the cup will likewise revolve and will travel progressively toward the bottom of the casing thereby expelling the 80 grease through the nozzle 3.

The cover 5 may be readily removed and the parts withdrawn for the purpose of filling the cup. The cap 4 acts as a good bearing to steady the movements of the stem, 85 and in connection with the plunger cup will effectually prevent any wabbling of the stem.

Since it is merely necessary that the plunger cup should revolve with the stem and should at the same time have movements lengthwise thereof, it is not at all essential that the shape of the stem should be rectangular in cross section, since it will be evident that so long as the stem is not a plain cylinder the operation of the parts 90 will be the same as above set forth, and therefore I do not wish to be limited in this respect.

By making the stem perfectly plain and causing the plunger cup to revolve with the stem, the latter will not be projected, after the manner of a piston rod, beyond the top of the casing, and, moreover, I do away with extra parts such as would be necessary if 100 the stem were threaded and engaged with the plunger cup, because in such an instance it would be necessary to provide some means to prevent the rotation of such cup, the sole 105 aim of my improvement being to provide an 110

exceedingly simple device with a minimum number of parts.

Having thus described my invention what I claim as new and desire to secure by Letters Patent is:—

1. A lubricator comprising a casing provided with an open upper end, a cap rotatably seated on the open end of the casing, a cover inclosing the cap and frictionally engaging the exterior of the open end of the casing, a stem extending through the cap and cover and into the casing, the stem being rotatable relative to the cover but not rotatable relative to the cap, a plunger carried by the stem, a collar carried by the stem and abutting the inner surface of the cap, and a second collar carried by the stem and abutting the outer surface of the cover.

2. A lubricator comprising an internally threaded casing provided with an open upper end, a cap rotatably seated on the open upper end of the casing, a cover inclosing the cap and frictionally engaging the outer surface of the open end of the casing, a stem extending through the cover and cap and into the casing, the stem being rotatable relative to the cover and held against rotation relative to the cap, and a plunger carried by the stem.

In testimony whereof I affix my signature in presence of two witnesses.

NORMAN W. CUMMINS.
